Primary Examiner — Angela J Lee*Assistant Examiner* — Shawn T Gingrich(57) **CLAIM**

The ornamental design for a GFCI adapter, as shown and described.

DESCRIPTION

FIG. 1 is a top-side perspective view of the GFCI adapter showing our new design;

FIG. 2 is a bottom perspective view thereof;

FIG. 3 is a another top-side perspective view thereof;

FIG. 4 is a side perspective view thereof;

FIG. 5 is a top down view thereof;

FIG. 6 is a bottom view thereof;

FIG. 7 a right-side view thereof;

FIG. 8 is a left side view thereof;

FIG. 9 is a front view thereof; and,

FIG. 10 is a rear view thereof.

The broken lines in the drawings represent portions of the GFCI adapter that form no part of the claimed design.
